John Crabtree
BY *John Aldiederschein*
ATTORNEY.

UNITED STATES PATENT OFFICE.

JOHN CRABTREE, OF PHILADELPHIA, PENNSYLVANIA.

TOOL-HOLDER.

SPECIFICATION forming part of Letters Patent No. 349,923, dated September 28, 1886.

Application filed November 23, 1885. Serial No. 123,626. (No model.)

To all whom it may concern:

Be it known that I, JOHN CRABTREE, a citizen of the United States, residing in the city and county of Philadelphia, State of Pennsylvania,

have invented a new and useful Improvement in Tools and Tool-Holders, which improvement is fully set forth in the following specification and accompanying drawings, in which—

10 Figure 1 represents a partial plan view and partial horizontal section of a tool and tool-holder embodying my invention. Fig. 2 represents an end view thereof, the holder being at right angles to the position shown in Fig. 1. Fig. 3 represents a plan view of a modification thereof. Fig. 4 represents a vertical section of a portion of such modification. Fig. 5 represents a side view of another modification thereof.

20 Similar letters of reference indicate corresponding parts in the several figures.

My invention relates to improvements in tool-holders; and it consists in constructing the same with an opening which is diagonal 25 in direction both longitudinally and laterally, as hereinafter described, whereby the said holder is readily adapted to the adjustment and desired operation of the tool.

Referring to the drawings, A represents a 30 tool-stock constructed of a bar of iron or steel, which is of angular form in cross-section, and adapted to be fitted in a tool-post or othersuitable support in a lathe or other machine for cutting, boring, or other working purposes.

35 B represents a tool, which is formed of round steel and fitted in a circular opening, C, in the bar or holder A, said tool being secured to the stock by means of a set-screw, D, as in Figs. 1, 2, and 5, or a gib, D', and wedge D², as in 40 Figs. 3 and 4; it being noticed that the opening, and consequently the tool, extends in a

diagonal direction both longitudinally and laterally, as seen in Figs. 1 and 2, and the point of the tool is salient for action upon the metal.

It will be seen that the tool may be readily fitted to the stock, adjusted therein, and removed therefrom in a most convenient manner.

When the tool is dull or broken, it may be 50 displaced and sharpened or repaired without disturbing the stock or post, this being a great convenience to the workman. Furthermore, when the tool is worn out or irreparable, it being comparatively a short piece, the loss is 55 slight, the holder remaining intact and readily permitting the application of a fresh tool.

The circular opening in the holder adapts the tool to be turned as desired, in order to set the point of the tool relatively to the work 60 to be accomplished.

Owing to the diagonal arrangement both longitudinally and laterally of the opening in the holder, the tool is tightly retained therein and firmly withstands the thrust to which it 65 is subjected when in use.

Having thus described my invention, what I claim as new, and desire to secure by Letters Patent, is—

The stock A, of angular form in cross-section, having an opening, C, therein, said opening extending diagonally both longitudinally and laterally, being circular in horizontal section, a round tool inserted in said holder, and fastening devices securing said tool, all combined substantially as and for the purpose set forth.

JOHN CRABTREE.
